United States Patent

Des. 235,943
Patented July 22, 1975

235,943

SEAT

Stapleton Long, Morristown, Tenn., assignor to The
Berkline Corporation, Morristown, Tenn.

Filed Sept. 6, 1974, Ser. No. 503,896

Term of patent 7 years

Int. Cl. D6—01

U.S. Cl. D6—37

FIG. 1.

FIG. 2.

FIG. 3.

FIG. 4.

FIG. 1 is a front perspective view of a seat showing my design in the form of a chair.

FIG. 2 is a view in side perspective thereof.

FIG. 3 is a front perspective view of a seat showing my design in the form of a sofa.

FIG. 4 is a view in side perspective thereof.

The sides of the seat not shown are mirror images of the sides shown while the rear surfaces thereof are conventional.

I claim:

The ornamental design for a seat, as shown.
